(57) **CLAIM**

The ornamental design for a V-shaped patch on tool bags
design, as shown and described.

DESCRIPTION

FIG. 1 is a front-right perspective of applicant's design.

FIG. 2 is a front elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a left side elevational view thereof;

FIG. 8 is a depiction of the V-shaped patch on tool bags
design, wherein said carrier is not a part of the design, but
rather the carrier is used to show placement; and,

FIG. 9 is a depiction of multiple V-shaped patch on tool bags
design, wherein said carrier is not a part of the design, but
rather the carrier is used to show placement.

The broken line showing of environment in the drawings is
included for the purpose of illustrating only and forms no part
of the claimed design.
